MANUFACTURING COMPANY, OF MILWAUKEE, WISCONSIN, A CORPORATION OF
DELAWARE.**

COMMINUTING MILL.

Application filed March 8, 1928. Serial No. 259,968.

- This invention relates generally to improvements in the construction and operation of rotary comminuting mills for reducing granular material to a fine powder.
- 5 An object of the invention is to provide a new and useful comminuting mill for effectively reducing granular material such as cement clinker, to a fine powder. Another object of the invention is to provide im- 10 proved classifying means for separating the material being treated in a comminuting system, into several grades, and for delivering the separated grades to apparatus which is especially adapted to subsequently effectively 15 treat the several grades. A further object of the invention is to provide improved screening mechanism operable directly by the movement of a comminuting mill, and means associated with the screen for distributing the 20 screened material. Still another object of the invention is to provide an improved attachment for rotary comminuting mills wherein the material is reduced by stages, which will insure delivery of material of 25 proper mesh to each of the several comminuting chambers for effecting the several stages of reduction. A further object of the invention is to provide an improved multiple compartment comminuting mill wherein freely 30 tumbling comminuting bodies are utilized, and in which the action of these bodies is not interfered with by screens or the like. These and other objects and advantages of the invention will be apparent in the course of the 35 following description.
- A clear conception of an embodiment of the invention and of the mode of operating devices constructed in accordance therewith, may be had by referring to the drawing ac- 40 companying and forming a part of this speci- 45 fication in which the various parts have been referred to by suitable reference characters.
- The single figure of the drawing is a relatively-diagrammatic illustration of a multiple compartment tube mill having the im- 50 proved classifying or screening device associated therewith.
- In the drawing, the multiple compartment comminuting mill comprises in general 55 an elongated shell or drum 5 supported for rotation about a substantially horizontal axis, by means of feed and discharge end trunnions 6, 7, and having therein two partitions 39, 40 which divide the interior of the drum into successive comminuting chambers 2, 3, 4 hav-
- ing freely tumbling comminuting bodies 29, 30, 31 therein, respectively.
- The coarse grinding chamber 2 may be formed of larger diameter than the others, and may also be provided with a tapered portion as shown, at the discharge end thereof. The feed trunnion 6 located at the inlet end of the chamber 2, is provided with a feeder 9 cooperating with a tapered end liner 28, for introducing the untreated material to the mill. After being initially reduced in the chamber 2 by the large comminuting bodies 29, the material is delivered through an end screen 10 and through a series of peripheral openings 36, to one end of an outer screen 11. The screen 11 is attached directly to and is rotatable with the drum 5, and has the end thereof remote from the openings 36, open for the discharge of rejects which fail to pass through the screening openings during rotation of the screen. Located directly beneath the annular outer screen 11 is a stationary receptacle 13 forming a trough one end of which is closed by a wall 15 secured to the receptacle and extending in close proximity to the peripheral edge of the screen. A spiral conveyer 12 which is attached directly to the screen 11 cooperates with the receptacle 13 to urge material delivered thereto through the screen 11, along the receptacle in a direction away from the wall 15. A stationary receptacle 14 disposed at the end of the screen 11 adjoining the wall 15, is adapted to receive the rejects from the interior of the rotating screen 11. The drum 5 is provided with spiral scoops 18 at the medial portion of the coarse grinding chamber 2, and these scoops 18 are adapted to return the screen rejects entering the receptacle 14, to the interior of the chamber 2 for further reduction.
- The material delivered from the receptacle 13 by the conveyer 12, is discharged into a stationary receptacle 16 from whence it is automatically removed and injected into the feed end of the intermediate comminuting compartment 3, by means of spiral scoops 17 secured to and operable by the movement of the drum 5. In the intermediate chamber 3, the classified material introduced by the scoops 17, is further reduced by the tumbling comminuting bodies 30, the material being eventually delivered through an internal end screen 19 and peripheral openings 21 to a screw conveyer 20.
- The screw conveyer 20 delivers the mate-

rial discharged from the intermediate chamber 3 to a bucket elevator 22 which raises the said material and delivers the same to an air separator. The air separator consists 5 of a housing within which is located a distributing rotor 33 and a fan 32. The rotor 33 is disposed directly above a hopper 34 which is adapted to collect the oversize and to deliver the same through a spout 37 to the stationary receptacle 16, from whence this oversize is delivered together with the material received from the receptacle 13, to the intermediate comminuting compartment 3. The housing of the dust collector is provided with 10 a conical bottom 35 forming a collecting hopper for the fine material removed by the air separator. The conical bottom 35 delivers fine material deposited thereon, through a spout 38 to a stationary receptacle 23 located 15 below the inlet end of the fine grinding compartment 4. The operation of the air separator is well known to those skilled in the art, the material delivered to the rotor 33 being thrown outwardly toward an interior 20 baffle by centrifugal force, and the air current induced within this baffle by the fan 32 picking up the lighter particles, which, after passing through the fan, are thrown outwardly against the housing wall and eventually 25 drop by gravity upon the conical bottom 35 from which they are discharged by gravity.

The feed end of the fine grinding compartment or chamber 4 is provided with peripheral scoops 24 which remove the relatively fine material from the stationary receptacle 23 and introduce the same into the chamber 4. The tumbling comminuting bodies 31 within the chamber 4 reduce the graded 30 material thus admitted, to a fine powder. The finally reduced material is eventually discharged through an internal grating 25, into the path of elevating vanes 26 which lift the final product and discharge the same 35 through an opening 27 in the trunnion 7, in an obvious manner. Continuous rotation may be imparted to the drum 5, the scoops 17, 18, 24, and to the screen 11, by means of a driving gear 8 located at the discharge end of 40 the mill.

From the foregoing description it will be noted that during normal operation of the mill, the revolving screen 11 serves to separate the oversize from the relatively fine 45 material discharged from the coarse grinding chamber 2, and also serves to deliver the oversize and the fine material to stationary receptacles located closely adjacent to the respective portions of the mill to which the 50 separated materials are to be subsequently delivered. The scoops 17, 18 may then be utilized to return the respective materials to the mill for further grinding by comminuting bodies which will effectively treat these 55 materials. By attaching the conveyer 12 di-

rectly to the screen 11 minimum head room is required in order to deliver the fine material from the receptacle 13 into the receptacle 16. The screen 11 may obviously be made of any desired length in order to insure effective 70 removal of the fines, and the spiral return scoops 18 serve to deliver the rejects to the medial portion of the comminuting chamber 2 so that they may be effectively reduced during subsequent travel through this chamber. 75 The classifying devices besides being highly effective in operation, is also extremely compact and accessible and does not in any manner interfere with the free tumbling action of the comminuting bodies within the mill. 80

It is to be noted that the novel use of an air separator for the purpose of classifying preliminarily reduced material in order to separate the fines from the coarse material, and the further reduction of the separated fine 85 material alone in a comminuting chamber, while being disclosed in connection with the present invention, forms no part thereof, and is the subject of a copending application Serial No. 256,209, filed February 23, 1928. 90 The present invention is however especially adapted for use in connection with this prior invention, in order to insure the production of extremely fine pulverulent material such as is required in the manufacture of cement. 95

It should be understood that it is not desired to limit the present invention to the exact details of construction and operation herein shown and described for various modifications within the scope of the claims may 100 occur to persons skilled in the art.

It is claimed and desired to secure by Letters Patent:

1. In combination, a rotary drum forming a comminuting chamber, a screen communicating with said chamber and rotatable with said drum, a stationary receptacle disposed beneath said screen, a second stationary receptacle communicating with the interior of said screen, a conveyer secured to said screen 105 and movable in said first mentioned receptacle to urge material delivered thereto through said screen along said receptacle longitudinally of the axis of said drum, and means for returning to said drum material delivered from said screen to said second receptacle. 110

2. In combination, a rotary drum forming a comminuting chamber, a screen communicating with said chamber and rotatable with said drum, a receptacle independent of said drum disposed beneath said screen, a second receptacle independent of said drum communicating with the interior of said screen, a conveyer operable by the rotation of said 120 drum to urge material delivered to said first mentioned receptacle through said screen toward an end of said receptacle, and means for returning to said drum material delivered 125 from said screen to said second receptacle. 130

3. In combination, a rotary drum forming a comminuting chamber, a screen surrounding and communicating with said chamber, said screen being rotatable with said drum, a receptacle independent of said drum disposed beneath said screen, a second receptacle independent of said drum communicating with the interior of said screen, a conveyer secured to said screen and movable thereby within said first mentioned receptacle to urge material delivered through said screen toward an end thereof, and means rotatable with said drum for returning thereto material delivered from said screen to said second receptacle.
4. In combination, a rotary drum forming a comminuting chamber, a screen surrounding and communicating with said chamber, said screen being rotatable with said drum, a stationary receptacle disposed beneath said screen and formed to receive material passing therethrough, a second stationary receptacle for receiving from said screen material which fails to pass therethrough, means for returning material which fails to pass through said screen to said chamber, and means operable by the movement of said screen for urging material delivered to said first mentioned receptacle therealong longitudinally of the axis of rotation of said drum.
5. In combination, a rotary drum forming a plurality of comminuting chambers, a screen disposed concentrically of said drum and communicating with one of said chambers, said screen being rotatable with said drum, a stationary receptacle disposed beneath said screen and formed to receive material passing therethrough, a second stationary receptacle for receiving from said screen material which fails to pass therethrough, means for returning material which fails to pass through said screen to said chamber, a conveyer secured to said screen and rotatable therewith to urge material within said first mentioned receptacle toward an end of said screen, and means associated with said drum beyond said end of said screen for returning said material to another of said chambers.
6. In combination, a rotary drum forming a comminuting chamber, a screen communicating with said chamber, said screen surrounding said drum and being attached directly thereto so as to rotate therewith, a stationary receptacle disposed beneath said screen, a second stationary receptacle for receiving rejects from said screen, a spiral conveyer secured directly to the periphery of said screen and cooperable with said first mentioned receptacle to urge screened material therealong, and a scoop carried by said drum for returning rejects from said second receptacle to said chamber.
7. In combination, a rotary drum forming a comminuting chamber, a screen surrounding said drum and extending therealong, said screen being attached directly to said drum and being spaced from the exterior thereof, a stationary receptacle disposed beneath said screen and forming a trough spaced from the external screen surface, a second stationary receptacle for receiving rejects from the interior of said screen, a spiral conveyer secured directly to said external screen surface and cooperable with said trough to urge material passing through said screen along said trough longitudinally of the axis of said drum, and a scoop carried by said drum for returning rejects from said second receptacle to said chamber.
8. In combination, a rotary drum forming a plurality of comminuting chambers, a screen surrounding said drum and communicating with an end of one of said chambers, said screen being attached directly to said drum and extending therealong, a stationary receptacle for receiving rejects from the interior of said screen, means associated with said drum beyond the end of said screen which communicates with said chamber for returning rejects to said chamber, a second stationary receptacle disposed externally of said screen, a spiral conveyer secured directly to said screen for urging material delivered to said second receptacle longitudinally of said screen and away from said rejects returning means, and means for returning said last mentioned material to another of said chambers beyond the end of said screen.

In testimony whereof, the signature of the inventor is affixed hereto.
